RETAINING CLIP FOR FINGER RINGS

Dean Walley, Decatur, Ill.

Application May 13, 1954, Serial No. 30,449

Term of patent 3½ years

(Cl. D45—1)

Figure 1 is a side elevational view of a retaining clip for finger rings showing my new design.

Figure 2 is an end elevational view thereof.

Figure 3 is a bottom plan view thereof; and

Figure 4 is a perspective view thereof, drawn on an enlarged scale.

The broken line disclosure of finger rings in Figs. 1, 2 and 3 are included for illustrative purposes only.

I claim:

The ornamental design for a retaining clip for finger rings, as shown and described.
